UNITED STATES PATENT OFFICE.

WALTER B. WALKER, OF NEWCASTLE, WASHINGTON, ASSIGNOR OF ONE-HALF TO MARS FORTIN, OF NEWCASTLE, WASHINGTON.

CAR COVER.

Application filed October 20, 1922. Serial No. 595,846.

To all whom it may concern:

Be it known that WALTER B. WALKER, a citizen of the United States, residing at Newcastle, in the county of King and State 5 of Washington, has invented certain new and useful Improvements in Car Covers, of which the following is a specification.

This invention relates to car covers and more particularly to covers for coal cars 10 used in mines.

An object of the invention is to provide a car cover, which is collapsible or foldable, and when folded will lie in the plane of the sides of the car. Such a construction 15 is particularly adapted for use on coal cars in mines where attachments to a car, which project beyond the outline of the car, will come in contact with bracing timbers and the like and be torn off.

Another object of the invention is to 20 provide a cover structure formed of a plurality of leaf members mounted on levers, half of the leaves being foldable into superimposed relation on each side of the car and

25 in cover forming relation to have the adjacent edges overlap, means being provided to raise the center leaves higher than the others to form a sloping cover structure, and locking means being provided on the 30 levers for locking the leaves in cover forming relation.

Other objects and the details of construction will appear in the following detailed description and in the claims.

In the drawings:

Fig. 1 is a top plan view with the device in cover forming position.

Fig. 2 is a sectional view on line 2—2 of Fig. 1.

Fig. 3 is a top plan view with the device folded onto the sides of the car body.

Fig. 4 is a side elevation of a portion of the car with the cover in folded position.

1 indicates a car body of the type used 45 particularly in coal mines, having side walls 2, front end 3, and rear end 4 extending above the side walls and provided with an upper edge sloping toward the side walls as indicated at 5. The forward portion of 50 the side walls and front end are cutaway as shown at 6.

Levers 7 are pivotally and movably mounted on pivots 8 on the upper edge of the side walls 2 adjacent the rear end 4 55 and levers 9 are similarly mounted on the

side walls in the cutaway portion 6 near the juncture thereof with the main portion of the side walls. A plurality of leaf members 10 forming cover sections are pivotally mounted on the underside of the levers 7 60 as shown at 11 in spaced superimposed relation, and similarly secured to levers 9 on the upper side as shown at 12. Spacing sleeves 13 are provided on the pivot pins to hold the leaves in their relative positions. 65 When the leaves are in cover forming relation as shown in Fig. 1, the edges overlap as indicated at 14 in Figure 2, while cam members 15 secured inside the car body engage the underside of the rear end of the 70 leaves and raise the leaves and levers 7 to the inclined position shown particularly in Fig. 2, and cam members 16 engage levers 9 at the front end of the cover for inclining the front end to correspond with the 75 rear end. Handles 17 are mounted on the upper leaf on each side so that the covers may be conveniently and manually operated.

One lever 7 is provided with an upstanding shank 18 formed into a laterally extending handle 19, and the other lever 7 carries a plate 20 formed with a notch 21 to receive the shank 18, for locking the cover sections on each side of the car body in cover forming relation. A plate 22 is mounted on one lever 9 and adapted to engage under the end of the other lever 9 for supporting the end of the other lever when in cover forming position relative thereto. 90

The cover is seen in cover forming position in Figs. 1 and 2, in which the cam members hold the cover sections to provide an incline from the center to the sides, the covers being in overlapped relation and the 95 handle 19 and plate 20 securing the cover portions securely together. In this position, the cover will protect the contents of the car from falling out over the sides and rear end when the car is on a steep incline or rounding curves when the material would have a tendency to fall out.

The cover may be folded when desired by disengaging shank 18 from notch 21 in plate 20 and moving the levers about their pivots 105 into the plate of the side walls when the leaves 10 will lie in superimposed relation over the top edge of the side walls, one half of the cover being carried on each wall, and the covers lying substantially within 110

the plane of the walls, as clearly shown in Figs. 3 and 4. In this folded position, it will be obvious that the parts do not project beyond the plane of the body and therefore will not contact with obstacles near the track as the car moves along, as would be the case of covers pivoted on the upper edge of the side walls and free to swing back and forth. At the same time, free access is had to the interior of the body for loading material.

What I claim is:

1. A car cover, including a plurality of leaves supported on the sides of a car and extending over the body in overlapped relation to form a cover, said leaves being adapted to be folded into the plane of the sides of the car in superimposed relation.
2. A car cover, comprising a pair of levers pivotally mounted on each side of the car, and a plurality of leaves pivotally mounted on each pair of levers and adapted to lie in superimposed relation, said levers being operable for extending the leaves into cover forming relation or folding them into superimposed relation on the sides of the car.
3. A car cover, comprising a pair of levers pivotally mounted in spaced relation

on each side of a car, a plurality of leaves pivotally secured to each lever in superimposed relation, said levers being adapted for operation to move the leaves into cover forming relation, and cam elements mounted on the sides of the car for engaging said levers and raise the center portion higher than the edge portions of the cover.

4. A car cover, comprising a pair of levers pivotally mounted in spaced relation on each side of a car, a plurality of leaves pivotally secured to each lever in superimposed relation, said levers being adapted for operation to move the leaves into cover forming relation, cam elements mounted on the sides of the car for engaging said levers and raise the center portion higher than the edge portions of the cover, and means for detachably securing the ends of oppositely disposed levers together in cover forming position.

In testimony whereof I affix my signature 50 in the presence of two witnesses.

WALTER B. WALKER.
